UNITED STATES PATENT OFFICE.

JOHN MAKANT CRYER AND WILLIAM ERNEST BULLEN, OF POULTON-LE-FYLDE, ENGLAND.

ELECTRIC SHUTTLE-MOTION FOR LOOMS.

SPECIFICATION forming part of Letters Patent No. 665,186, dated January 1, 1901.

Application filed September 4, 1900. Serial No. 29,024. (No model.)

To all whom it may concern:

Be it known that we, JOHN MAKANT CRYER, machinist, of Breck Villas, Poulton-le-Fylde, and WILLIAM ERNEST BULLEN, electrical engineer, of 1 Alexandra Villas, The Green, Poulton-le-Fylde, in the county of Lancaster, England, subjects of the Queen of England, have invented certain new and useful Improvements in Methods of Operating the Shuttle Employed in Looms for Weaving and Apparatus for Effecting the Same, of which the following is a specification.

This invention relates to a new or improved method of operating the "shuttle" employed in looms for weaving and apparatus for effecting the same; and it consists in means for throwing the shuttle through the "shed" by electricity, thereby dispensing with the old or present system of operating the same by means of pickers operated from each end of the loom by picking-sticks, thereby dispensing with the noise caused by picking motions, at the same time rendering it impossible for the shuttle to fly out from the loom, thus minimizing the risk from accident to the weaver so prevalent hitherto.

Figure 1 is a longitudinal front elevation of so much of a loom as is necessary to illustrate our invention for a new or improved method of operating the shuttle employed in looms for weaving and apparatus for effecting the same; Fig. 2, a plan of Fig. 1; Fig. 3, a transverse sectional elevation through line A' B' in Fig. 1; and Fig. 4 a sectional end view of brushes mounted on sliding frame.

In all the figures the same letters are employed to indicate corresponding parts.

A designates the loom sides or frames; B, a crank-shaft; C, a cam or tumbler shaft; D, a "slay," E, "slay-swords;" F, a reed; G, a driving-pulley; H, a loose pulley, and Z the metallic shuttle.

Under the slay D is disposed the electro-magnet or magnets I, mounted on the frame K, located or mounted so as to slide or travel the necessary width of the loom on the slide-bar or slide-bars L, carried from the slay D by means of the brackets J, attached thereto in any convenient manner. If desired, the slay D may be provided with a slot or slots to insure of the efficiency of the magnet or mag-

nets I operating on the shuttle Z. The sliding frame or sliding yoke K is moved or traveled in both directions by means of the wire or cord M, which passes over and under the pulleys a to the scroll O, mounted on the shaft or center N, located in the fixings P, secured to any convenient part of the framework of the loom or to the floor. On the shaft or center N is mounted the differential cam R, which is actuated in both directions by the bands or cords S, which pass over the guide-pulleys T to the treadle-levers U, operated alternately by the cams W from the cam or tumbler shaft C. As the cams W actuate their respective levers by the rotating action of the cam or tumbler shaft C, the differential cam R rotates the shaft or center N and the scroll O, by which action the wire or cord M is moved, so as to travel the sliding frame or sliding yoke K, with the brushes Y and electro magnet or magnets I, across the width of the loom in both directions, according to the operations of the cams W with the treadle-levers U. The brushes Y are mounted on the sliding frame or sliding yoke K and disposed so as to slide in contact with the upper and lower plates b, as shown in Figs. 1 and 4, the said plates b being mounted on the wood or other suitable bar f, carried by the brackets J'.

Electricity is supplied from a dynamo through the electric wire c to the terminal d, mounted on the plates b, located on the wood or other suitable bar f, from whence it passes through to the terminal e on the said plate b and through the wire g to the "switch" X, mounted on the "breast-beam" V of the loom, the switch X being coupled to the dynamo by the electric wire h, thus completing the circuit, by which action the shuttle Z is operated through the shed. The whole of the parts are insulated where necessary and protected in any convenient manner, as desired or required.

The electric wires c, g, and h are of such a length as to allow of the oscillating movements of the slay D.

Having now particularly described and ascertained the nature of our said invention and in what manner the same is to be performed, we declare that what we claim is—

1. In a loom, the combination with a metallic shuttle, of a magnet for actuating the same, a cord or wire for moving said magnet back and forth across the loom, a drum or scroll on which said cord is wound, a differential cam on the shaft on which said scroll is mounted, a guide-pulley, treadle-levers, cords passing around said guide-pulley and in opposite directions around said cam and having their ends attached respectively to said treadle-levers and to said cam, a cam-shaft and cams thereon adapted to engage said levers for alternately rotating said scroll in opposite directions, as and for the purpose set forth.

2. In a loom, the combination with the slay D and a metallic shuttle Z, above the same, of a sliding frame or yoke K, having contact-brushes Y thereon, an electro magnet or magnets I carried by the frame K and located beneath said slay D, electric contact-plates b insulated from each other and adapted to be engaged respectively by said brushes Y, an electric circuit including a switch X,

the plates b, the brushes Y and the magnets I, a scroll O, a cord or wire M connected at its opposite ends to said frame K and wound upon said scroll, a shaft N on which said scroll is mounted, a differential cam R on said shaft, a guide-pulley T, treadle-levers U, cords S passing around said guide-pulley, wound in opposite directions on said cam, and connected at their ends respectively with said treadle-levers and with said cam, a cam-shaft C and cams W on the shaft C adapted to engage said treadle-levers for actuating the same alternately, and thereby rotating said scroll O alternately in opposite directions, as and for the purpose set forth.

In testimony whereof we have hereunto set our hands in presence of two subscribing witnesses.

JOHN MAKANT CRYER.

WILLIAM ERNEST BULLEN.
